UNITED STATES PATENT OFFICE.

CHARLES F. WOOD, OF SUMMIT, NEW JERSEY.

DESIGN FOR A JEWELRY-SETTING.

Specification forming part of Design No. **11,409**, dated September 9, 1879; application filed June 19, 1879.

[Term of patent 3½ years.]

To all whom it may concern:

Be it known that I, CHARLES F. WOOD, of Summit, in the county of Union and State of New Jersey, have invented a new and Improved Design for Jewelry-Settings, of which the following is a specification.

In the accompanying drawing the design is shown as applied to the stone or setting of a ring.

My design is for the surface ornamentation of the setting.

A is the setting, having the design cut in its surface.

The design consists of a bird upon a branch or twig, as at *a*, and the representation of a panel at the base of the twig, as at *b*. To obtain a more ornamental effect, this design is produced in white and gold colors by inlaying

the metal, and the panel *b* is inlaid with diamonds or other white stones to represent eggs. The leaves of the twig are also inlaid with a diamond.

Having thus fully described my invention, I claim as new and desire to secure by Design Patent—

A design for settings of jewelry, consisting of a bird seated on a twig with a superposed leaf, having a single diamond and a subjacent panel with two diamonds, said diamonds being egg-shaped, and the whole inlaid in white and gold colors, as described.

CHARLES F. WOOD.
